E. NICHOLAS.

ASH SIFTER.

APPLICATION FILED NOV. 17, 1920.

1,380,832.

Patented June 7, 1921.

UNITED STATES PATENT OFFICE.

EDWARD NICHOLAS, OF CAMBRIDGE, MASSACHUSETTS.

ASH-SIFTER.

1,380,832.

Specification of Letters Patent. Patented June 7, 1921.

Application filed November 17, 1920. Serial No. 424,646.

To all whom it may concern:

Be it known that I, EDWARD NICHOLAS, British subject, and resident of Cambridge, in the county of Middlesex and State of Massachusetts, have invented certain new and useful Improvements in Ash-Sifters, of which the following is a specification.

This invention relates to ash sifters and is intended to provide a device of this kind adapted to conveniently take up unsifted ashes and sift them effectually without allowing the dust to escape from the sifter, convenient provision being made for the separate deposit of the cinders and the ash after the sifting operation is completed.

Ash sifters intended for this purpose are commonly made of sheet metal and in consequence even when doors are provided the buckling of the sheet metal under the strain of a load results in leaving gaps and cracks around the doors through which the fine ash dust can penetrate to the discomfort of the one using the device.

The present invention is intended to overcome this and other difficulties and comprises, generally speaking, a casing of suitable form divided longitudinally into separate compartments by a longitudinal screen forming a foraminous partition located between the top and bottom walls of the casing, the two compartments being left open across the opposite ends and on opposite sides of the partition to provide a capacious intake and outlet which are tightly closed by suitable doors or gates during the sifting operation.

This and other features of the invention will be particularly described in this specification and will be defined in the claims hereto annexed.

In the drawings I have illustrated a simple and convenient construction and arrangement embodying the principles of this invention in which:

Figure 1 is a longitudinal vertical section through the middle of the complete device.

Fig. 2 is a plan view thereof.

In the practice of the invention according to the form illustrated in the drawings, I provide a casing of any suitable material such as sheet metal comprising of a bottom 1, top 2 and opposite sides 3. The forward end of the bottom is turned back on itself at an angle by two folds or bends to form a triangular hollow reinforcing rib comprising the members 4 and 5, the former of which forms an inclined plane extending down to

a point to facilitate scooping up the ashes into the interior of the casing. The vertical portion 5 of this triangular rib closes the narrow converging front end of the casing and affords a substantial support for the attachment of the forward end of the foraminous partition or screen 16. At the same time it prevents the accumulation of material in the constricted forward end of the lower compartment.

In the form shown, the top of the casing is made considerably shorter than the bottom so that the opposite sides 3 have their forward edges extending in an oblique direction toward the front. This oblique portion of the sides is turned inwardly to form opposing flanges 6 which both serve to stiffen this part of the casing and also serve as an outside guide for the sliding door 8.

At a short distance inside of the lips or flanges 6 and extending parallel thereto are secured to the side walls 3 angle plates 7 so as to leave a narrow intervening space between the inturned members of the angle plates and the parallel inturned lips or flanges 6 corresponding to the thickness of the sliding door 8 for which the angle plates 7 and flanges 6 form runways or grooves.

The gate is provided with a hook or handle 9 to facilitate pushing it in or out.

The rear end of the casing is closed by an end wall or plate 10 which may be riveted or otherwise secured to the top and side walls of the casing and which terminates a substantial distance above the bottom 1.

Adjacent to and parallel with said end wall 10 is secured a partition plate 11 which extends about half-way down to the bottom from the top of the casing. The lower end of this inside wall is preferably turned in to form a flange 18 which forms an anchorage or support to which the rear end of the foraminous screen 16 is secured.

The plates 10 and 11 are spaced apart sufficiently to form a runway or guide for the sliding gate or door 13 which is inserted between them and which is given a height about equal to one-half the height of the casing. Normally this sliding rear door 13 when closed is overlapped by the end wall 10 to form a secure support and its lower edge is slit and supported by an angle iron 12 extending across and secured to the bottom 1. Above the middle of the top edge of the door 13 there is formed a small circular hole 15 through which a pull rod 14 is in-

serted which is soldered or otherwise connected to the middle portion of the upper edge of the door 13.

The reinforcing of the front and rear ends of the casing in the manner described serves to give the casing great stiffness or rigidity adjacent to the sliding doors so as to prevent the middle walls from bulging apart and leaving cracks for the escape of 10 the fine dust during sifting.

It will be noticed that the front end of the screen is fastened to the vertical flange 5 which forms the inclined receiving and stiffening rib at the front edge so as to 15 present no obstruction to the flow of ashes onto the screen when the device is used as a scoop to scoop up the ashes.

Suitable handles 19 and 20 are secured preferably to the rear end of the top walls 20 so that the device may be conveniently grasped for shaking or other manipulation.

In practice the door or sliding gate 8 is pulled open and the casing is then used as a scoop to scoop up a supply of ashes from 25 the floor after which the gate is closed and the ashes sifted by shaking.

When the sifting operation has been completed the dust or ash will be in the lower compartment while the coarser clinkers and 30 cinders will be in the upper compartment. Each door may then be opened the ashes being discharged from the front end into a suitable receptacle and the cinders discharged from the rear end.

35 What I claim is:

1. In an ash sifter, the combination of a casing, an interior screen extending lengthwise of the casing and forming a foraminous partition dividing the casing into upper and lower compartments, open at their 40 opposite ends to form respectively an intake and outlet, and doors mounted in said casing to tightly close said open ends to prevent the escape of dust during the sifting operation, substantially as described.

2. In an ash sifter, the combination of a casing whose bottom is extended forwardly beyond the front edge of the casing top, and is bent back upon itself to form a closed 50 hollow tapered reinforcing ledge, a door arranged to close the open front end of said casing and abut against the rear upper portion of said ledge, a rear wall closing the upper half of the rear end of said casing 55 and a door arranged inside said wall to close the open lower end of said casing, and a partition screen extending lengthwise of said casing and secured at its front end to the rear portion of said ledge, substantially 60 as described.

3. In an ash sifter, the combination of a casing whose bottom is provided at its front

end with a hollow tapered reinforcing ledge furnishing an abutment forming a stop shoulder for a sliding door, a partition 65 screen extending lengthwise of said casing to form upper and lower compartments, a rear end wall closing the upper part of the rear end of the casing, a sliding door arranged to close the lower part of the rear 70 end below said screen, and means passing through a restricted opening in the casing top to open and close said door and an obliquely mounted door arranged to close the front end of said casing above said 75 ledge, substantially as described.

4. In an ash sifter, the combination of a casing comprising top, bottom and side walls, the bottom projecting beyond the sides and the front edges of the sides having 80 oblique edges extending from the front edge of the top to the front of the bottom, said oblique edges being inturned to form door retaining flanges, reinforcing guide strips secured to the sides adjacent to and 85 parallel with said inturned flanges to form runways, a sliding door mounted between said runways to close the open front end, a rear wall closing the upper portion of the rear end of the casing door, supporting 90 guides secured to the casing and a sliding door arranged to close the lower rear end from side to side, and a partition screen dividing the casing into upper and lower compartments, substantially as described. 95

5. In an ash sifter, the combination of a casing comprising top, bottom and side walls, a screen arranged lengthwise in said casing to divide it into upper and lower compartments, each compartment being 100 open from side to side at one end opposite to the open end of the other and each having a sliding door arranged to tightly close its open end, reinforcing means secured to the ends of the casing in position to support 105 and guide the respective doors, substantially as described.

6. In an ash sifter, the combination of a casing comprising top, bottom and side walls, spaced cross walls secured to the rear 110 end of the casing to extend across and close the upper portion of said end, a slideable door interposed between said walls to close the lower portion of said end, an inclined ledge member extending across the front end 115 of the bottom, a partition screen extending from said inner rear wall, to the rear part of said ledge, and a sliding door arranged to close the front end of the casing above said ledge and said screen, substantially as 120 described.

In witness whereof, I have subscribed the above specification.

EDWARD NICHOLAS.
